DROP SIDE FOR FOLDING CRIBS

Harry M. Shealey, Hagerstown, Md.

Application July 22, 1946, Serial No. 685,535

3 Claims. (Cl. 5—100)

1

This invention relates to baby cribs, and more particularly to folding or collapsible cribs.

An object of this invention is to provide an improved folding or collapsible crib which will in its folded position require a minimum of space whereby the crib may readily be stored in hotel rooms, apartments, and in a vehicle while traveling.

Another object of this invention is to provide an improved collapsible crib which may be changed from either the folded or extended position very readily with a minimum of effort and requiring the use of no tools for the change and whereby there will be no loose or unattached parts to be scattered or lost.

Another object of this invention is to provide a folding bed of the kind to be more specifically described hereinafter in which the springs and bedding may be folded within the folded crib whereby the crib will be completely self contained with bedding and springs.

Another object of this invention is to provide a collapsible crib having full adjustable side panels which may be folded intermediate their length one end of each being quickly detachable from one of the end panels for folding the crib.

Still another object of this invention is to provide a crib of this kind having an end supported folding spring suspension, the spring panel being hingedly secured at each end to a solid spring end shelf firmly secured to the end panels for supporting the spring panel against concentrated impact load forces.

Yet another object of this invention is to provide a collapsible baby crib which is of a substantial construction to provide ample strength for such a bed yet remaining sufficiently light in weight to be readily portable and which is of such a simple construction as to be readily manufactured at an economical cost whereby it may be retailed at a reasonable price.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a top perspective view, partly broken away, of a crib constructed according to an embodiment of my invention.

Figure 2 is an enlarged perspective detail of

2

an upper rod fitting on the end panel of the crib, the end panel partly broken away.

Figure 3 is an enlarged perspective detail of a lower rod fitting on the end panel, the end panel and rod being broken away.

Figure 4 is a perspective detail view of the side panel fitting, the side panel being broken away.

Figure 5 is a perspective view of a modified type of crib, partly broken away.

Figure 6 is a perspective view of an upper rod fitting on the end panel, the rod and panel being broken away.

Figure 7 is a section taken on the line 7—7 of Figure 8.

Figure 8 is a detail perspective view of the removable side panel fitting, the panel being partly broken away.

Figure 9 is a perspective view, partly broken away, and partly in section of the folded crib in a covering.

Figure 10 is an enlarged perspective detail of a modified form of rod fitting.

Figure 11 is a perspective view of the hinge lock member.

Referring to the drawing the numeral 20 designates generally a collapsible crib having a pair of opposite end panels 21 and 22 and a pair of opposite folding side panels 24 and 25. A hinged folding spring panel 36 is hingedly secured at the ends thereof to the end panels 21 and 22.

The end panels 21 and 22 are formed with an outer frame having a pair of vertical side frame members 26 and 27 and a pair of horizontal frame members 28 and 29 fixedly connected between the vertical members 26 and 27 near the upper and lower ends of the vertical members. The lower horizontal frame members 29 are spaced upwardly from the lower end of the vertical members 26 and 27.

Fixed to the end panels 21 and 22 there is provided a shelf 30 which extends horizontally inwardly of the panels 21 and 22 and the lower horizontal frame members 29. The shelves 30 are fixedly attached to the end panels 21 and 22 by right angular brackets 31 which are fastened to the outer edges of the shelves 30 and the vertical frame members 26 and 27 by bolts 32 or other suitable fastening devices. Across the inner upper edge of the shelf 30 there is fixed one side 34 of a piano hinge 35 the barrel of which overhangs this inner upper edge.

The spring panel 36 of the bed 20, which may be of the flat strip spring type as shown in Figure 1 or a coiled type as shown in Figure 6, has secured to the end frame members 37 thereof the

cooperating other side 38 of the piano hinge 35 for hingedly engaging the shelves 30 in such a manner that the spring panel 36 may be moved upwardly relative to the shelves 30 and lie in a plane parallel to the plane of the end panels 21 and 22 inwardly between the panels 21 and 22. The spring panel is formed of two frames hingedly connected together at their inner ends by a piano hinge 39 as shown in Figure 9.

For connecting the side panels to the end panels there are provided rods 40 fixed to the vertical frame members 26 at each of the four corners of the bed 20. The rods 40 extend vertically along the length of the members 26 and are spaced inwardly therefrom. The rods 40 are secured to the frame members 26 at the upper and lower end of the rods 40 by brackets 41. The brackets 41 are substantially L-shaped having the arm 42 thereof secured to the member 26 by bolts 44 or other suitable fastening means and the extending arm 45 is of a shorter width than the arm 42 and is formed near its outer end with an annular opening 46 having a pair of opposed slots 47 extending radially therefrom. The ends of the rods 40 are counterbored and threaded for receiving a screw 48 and a pair of oppositely extending radial ears 49 are fixed on the ends of the rod 40 for aligning the rod 40 in the brackets 41. The screw 48 engages through the opening 46 and into the rod 40, the head of the screw bearing against the outer side of the bracket 41 for securing the rod 40 thereto. The upper and lower brackets 41 are of similar construction being merely overturned to suit the particular location.

A pair of opposite folding side panels 50 are slidably supported on the end panels 21 and 22. The side panels 50 are formed of a rectangular frame having vertical end members 51 and horizontal upper and lower members 52. The horizontal members 52 are divided midway their length and hingedly connected together by a hinge 54 on the outer surface of the members 52 whereby the side panels 50 may be folded inwardly. On each of the members 52 inwardly of the panels 50 there is provided a latch 55 for locking the members 52 in extended position. The latch 55 is formed of a pair of hinge sections 56 secured onto adjacent sections of the horizontal side panel frame members 52 each having a split barrel or a flange 57 on the cooperating ends thereof. A resilient strip of metal 58 is secured at one end to one hinge section 56 and is provided with a flange or keeper 59 engageable between the flanges 57 for holding the side panels 50 against folding. A handle 60 is attached to the free end of the keeper 59 for releasing the flange 59 from between the flanges 57 for folding the side panels.

At one end of each of the side panels 50 near the upper end of the vertical members 51 there is fixed a tubular guide member 61 engageable about the rod 40 for slidably mounting the side panels 50 to the end panels 21 and 22. The tubular guide members 61 extend vertically along a short distance of the length of the members 51 and extend outwardly from the outer ends thereof. Attaching plates 62 are secured to the guide tubes 61 by welding or other suitable fastening means and extend inwardly to be secured to the inner side of the vertical members 51 by screws or bolts. A resilient spring plate 64 is secured to the guide tube 61 on one side thereof at one end of the plate or member 64 and a lug 65 fixed on the free end of the spring 64 is adapted to be

urged through an opening 66 in the tube 61 and into one hole 67 of the rod 40 for latching the side panels 50 in selected vertical position relative to the end panels 21 and 22, the rods 40 being provided with a series of vertically spaced apart opening 67. A handle 68 is loosely attached to the free end of the spring 64 for disengaging the lug 65 from the tube 61 and rod 40.

At the other end of each of the side panels 50 a guide tube 61 is removably attached for removably and slidably attaching the panels 50 at one end to the end panels 21 or 22. The tube 61 is constructed the same at each end of the panel 50 with the exception of the plates 62. On the removable guide tubes 61 the plates 69 secured to each end of the tube 61 are formed with an inwardly extending lug 70 which is adapted to engage in an opening in the member 51 and with a threaded opening 71 above the lug 70. A plate 72 is secured to the opposite side of the member 51 from the plate 71 by screws 74 and a bolt 75 having a knurled head 76 engages through the plate 72, frame member 51 and threadably engages in the opening 71 of plate 69 for securing the plate 69 on to the frame member 51.

In Figure 11 there is shown a modified form of rod and fitting for attaching the rod 40 to the end panels 21 and 22. This rod 49a is flattened on the end and reverted into a U-shaped bracket 41a.

A modified form of end panel is shown in Figure 5 wherein a solid end wall 80 is fixed in the frames 21 and 22 to exclude drafts from the crib 20 and beneath the wall 80 there is provided a utility cabinet 81 for storing often used baby apparel, the cabinet 80 having a downwardly hinged door or closure 82.

In the use and operation of this folding crib 20, the normal position is shown in Figure 1, where the crib 20 is complete with a mattress 85, and is in position for use as a baby's bed. The side panels 50 may be adjusted vertically by pulling the handles 68 outwardly to release the lugs 65 from the rod 40 whereupon the side panel 50 may be slid upwardly or downwardly to another selected position.

To fold the crib 20 for storage or transportation the knurled screws 75 are removed from one end of the side panels 50, the screws 75 of opposite panels being at opposite ends thereof, whereby one guide 61 of each side panel 50 will be removed therefrom, remaining on its respective end 40, leaving each side panel 50 secured to opposite end panels 21 or 22. The side panels 50 are now moved to their uppermost position on the rods 40 and folded inwardly against their respective end panels 21 and 22 by releasing the keepers 59 from the latches 55. The spring panel 36 may then be folded upwardly from the inwardly extending shelves 30, with or without the mattress 85 in position. The crib 20 is now in its fully folded position and may be stored in a fabric covering 90 having a zipper closure or in other suitable storing containers or may simply be stored as folded.

I do not mean to confine myself to the exact details of construction herein disclosed but claim all variations falling within the purview of the appended claims.

Having thus described my invention, what I claim is:

1. A collapsible crib of the kind described comprising a pair of opposite end frames, an inwardly extending shelf on said frames, a spring panel hingedly secured to said shelves, a hinge

on said spring panel midway the length thereof whereby said spring panel may be folded upwardly, side panels on said crib, a hinge on said side panels whereby said side panels may be folded inwardly, vertical rods on said end frame spaced inwardly therefrom, tubes on the ends of said side panels slideable on said rods for slidably mounting said side panels on said end frames, correlated means carried by said tubes and rods for holding said side panels in selected position, a plate fixed to each of said tubes engageable with one side of a side panel, a second plate fixed on the opposite side of said side panel, a lug on said first plate engageable in said panel, and a screw slideable through said second plate and said panel threadably engaging said first plate.

2. A collapsible crib of the kind described comprising end panels, a folding bottom panel and folding side panels between said end panels, rods fixed on said end panels, tubular members on said side panels slideable on each of said rods, a spring-pressed pin on each of said tubular members engageable in an opening in the associated rod for positioning said side panels on each of said rods, a lug on said tubular members engageable in its associated side panel for positioning said tubular members thereon, screws projecting through apertures in said side members, and threaded means on said tubular members cooperating with said screws for removably securing said tubular members thereon.

3. A collapsible crib of the kind described comprising end panels, a folding bottom panel
